SAFETY RAZOR

Joseph E. McWilliams, New York, N. Y., assignor
to Gillette Safety Razor Company, Boston,
Mass., a corporation of Delaware

Application May 4, 1933, Serial No. 669,415
Renewed August 7, 1935

7 Claims. (CL. 30—72)

This invention relates to safety razors and more particularly to safety razors of the type in which a thin flexible or wafer blade is used and it is an object of this invention to provide an improved 5 razor of the type described in which the blade is securely held in shaving position by wedging means positioned to engage the blade by the usual operation of securing the cap in place. It is also an object of this invention to provide a blade designed to cooperate with the razor so as to be securely held in place by adjustable wedging means in the razor.

In the drawing—

Fig. 1 is a view of a razor constructed in accordance with this invention, looking at the cap end thereof;

Fig. 2 is a plan view of the blade guard with a blade in place thereon but not engaged by the wedges;

Fig. 3 is a view similar to Fig. 2 with the blade partly broken away, the cap stem in section and the wedges adjusted to engage the blade;

Fig. 4 is a partial central section taken as on the line 4—4 of Fig. 1 and showing the relative positions of the parts when assembled but with the wedges not adjusted to secure the blade in position;

Fig. 5 is a view similar to Fig. 4 showing the relative positions of the parts when the wedges are adjusted to engage the blade;

Fig. 6 is a plan view of the blade guard shown detached from the razor;

Fig. 7 is a transverse section of the blade guard taken as on line 7—7 of Fig. 6;

Fig. 8 is a plan view of the razor cap with a blade in position thereon, the blade being partly broken away in order to show the cap more clearly;

Fig. 9 is a view in elevation of the assembled 40 razor;

Fig. 10 is a perspective view of one of the wedging means shown detached from the blade guard; and

Fig. 11 is a plan view of a razor blade designed 45 to cooperate with the razor shown in Figs. 1 to 10.

As shown in the drawing a razor constructed in accordance with this invention comprises a cap 1 having a short centrally located threaded stem 2, a handle 4 having a threaded opening for receiving the stem 2 of the cap, and a blade guard 6 held between the cap 1 and the handle 2 and having a central opening 8 to receive the stem 2 of the cap. Extending in opposite directions from the central opening 8 of the guard 6 are 50 short slots 10 in which are movably mounted

wedge blocks 12 having curved faces at the opening 8 and having secured to the opposite faces pins 14 which extend through cylindrical openings 15 in the blade guard 6 leading from the slots 10. The outer ends of the openings 15 are enlarged, 5 as at 16, to receive springs 18 which are confined between the inner ends of the enlarged portions 16 of the openings 15 and the heads 20 on the pins 14, the springs 18 and pins 14 being arranged so as to hold the wedges 12 at the outer 10 ends of the slots 10, that is, to draw the wedges away from the central opening 8. The wedge blocks 12 have triangular shaped portions 22 which project above the surface of the guard 6 upon which the blade rests and taper towards the 15 central opening 8. At the opposite face of the guard 6, adjacent the central opening 8, the wedge blocks 12 are provided with extensions 24 which, with the inner faces of the wedge blocks, form portions of a sleeve surrounding the central 20 opening 8. The extensions 24 are provided with faces 26 shaped as portions of a cone tapering in a direction away from the guard 6 and cooperating with a correspondingly tapering face 28 surrounding the opening in the handle 4 for receiving the stem 2 of the cap 1.

The blade 30 used in this razor comprises the usual cutting edges 30a separated by the central slot and joined by the hinge portions 30b at the ends, the hinge portions projecting beyond the 30 cutting edges and forming therewith the recesses in which the usual lugs 32 on the cap 1 are received. The central slot in the blade is formed with substantially triangular portions which provide oppositely directed wedge engaging portions 35 30c having the inclined wedge engaging faces 30d positioned to be engaged by the corresponding faces 22d of the triangular portions 22 of the wedge blocks 12.

To assemble the razor for use the blade 30 is 40 placed on the guard 6 with the triangular openings in the blade fitting about the triangular portions 22 of the wedge blocks 12 in the guard, the cap 1 is placed on the guard with the lugs 32 of the cap engaging in the corner recess of the blade 45 and the stem 2 of the cap extending through the central opening 8 of the guard and the central opening of the blade. The cap 1 is provided with recesses 1a into which the wedge blocks 12 extend. The handle 4 is screwed upon the stem 2 50 drawing the cap 1 into engagement with the blade 30 and causing the cam face 28 of the handle to engage with the cam faces 26 of the wedge blocks and move the wedge blocks toward the center of the guard. Movement of the wedge 55

blocks 12 in the guard shifts the wedge blocks from the position shown in Figure 2 where the blade 30 is loosely mounted upon the guard 6 to the position shown in Figure 3 in which the triangular portions 22 of the wedge blocks 12 engage with the faces 30d of the blade 30 and hold the blade 30 rigid in the proper position for use. The engaging of the wedge blocks 12 with the blade 30 causes resistance to the inward movement of the handle 4 and insures the handle 4 drawing the cap 1 firmly into engagement with the blade 30. Engagement of the center portion of the blade 30 by the wedge blocks 12 reinforces the blade, stiffening the cutting edges thereof and reducing the tendency of the blade edges to vibrate.

Unscrewing the handle 4 from the stem 2 releases the cap 1 and permits the springs 18 to return the wedge blocks 12 to free the blade 30.

20 What is claimed is:—

1. In a safety razor, a blade guard, a blade having tapered openings therein, a cap, means to secure said cap to said guard and a plurality of tapered wedge blocks engaging in said openings in said blade and operated by said cap securing means into wedging engagement with said blade.

2. In a safety razor, a blade guard, a blade having an opening therein, a cap, a stem on said cap, wedging means mounted for reciprocation in said guard and fitting in said opening in said blade and a handle engaging said stem to secure said cap to said guard, said handle engaging said wedging means to force said wedging means into engagement with said blade.

35 3. In a safety razor, a blade guard having oppositely disposed wedging means movably mounted thereon, a blade on said guard having openings to receive said wedging means, a cap having

a threaded stem projecting through said blade guard and blade and a handle threaded to receive the stem of said cap and having a cam face engaging said wedging means and forcing said wedging means into engagement with said blade when threaded on said stem.

4. In a safety razor, a blade guard, a flexible blade having openings therethrough inwardly spaced from the ends thereof, wedging means movably mounted in said guard and engageable in said openings to fix said blade in position for use and a handle engaging said wedging means and operable to force said wedging means into engagement with said blade.

5. In a safety razor, a blade guard, a blade having a central longitudinal extending slot, wedging means fitting tapered portions of said slot, a cap having a stem projecting through openings in said guard and blade and means engaging said stem to draw said cap towards said blade, said means operating said wedging means longitudinally of said guard and blade to engage said blade.

6. In a safety razor, a blade guard, a blade, a cap having a threaded stem, wedge blocks and a handle having a threaded opening to engage said stem and a cam surrounding said opening and engaging said wedge blocks to engage said blocks and cap with the blade.

7. In a safety razor, a blade guard, a cap, a flexible blade, having openings therethrough, relatively movable wedge blocks mounted in said guard and projecting through said openings and means for simultaneously moving said blocks towards each other in said openings to engage said blade and engaging said blade between said cap and guard.

JOSEPH E. McWILLIAMS.
